UNITED STATES PATENT OFFICE.

GEORGE M. LATIMER, OF WATSONVILLE, CALIFORNIA.

BURNER.

1,257,891.

Specification of Letters Patent. Patented Feb. 26, 1918.

Application filed October 11, 1917. Serial No. 195,952.

To all whom it may concern:

Be it known that I, GEORGE M. LATIMER, a citizen of the United States, residing at Watsonville, in the county of Santa Cruz and State of California, have invented new and useful Improvements in Burners, of which the following is a specification.

This invention relates to a hydrocarbon burner.

10 It is the principal object of this invention to provide a hydrocarbon burner adapted to be supplied with liquid fuel under pressure and which will insure the thorough combustion of said fuel and an efficient production 15 of heat thereby.

Other objects will appear hereinafter.

The invention is illustrated, by way of example, in the accompanying drawings in which:

20 Figure 1 is a view in perspective illustrating the fuel burner and disclosing in a diagrammatical manner a fuel supply apparatus therefor.

Fig. 2 is a view in vertical section through 25 one of the burner units.

Referring more particularly to the drawings, 10 indicates an air tank which is adapted to be filled with air under pressure by a compression means such as the pump

30 11. This tank is connected with an oil tank 12. The oil in the tank passes out through a supply pipe 13. This pipe is led to a burner 14, as particularly shown in the drawings, and with which the present in-

35 vention is concerned.

The burner consists of a baffle floor 15 which is surrounded upon three sides by a retaining flange 16 and upon its remaining side by a baffle wall 17. As shown in the 40 drawings, the baffle floor and baffle wall are formed integral with each other and the flanges and are designed to accommodate three burner nozzles 18, 19 and 20, respectively. These burner nozzles are formed of 45 lengths of pipe which extend vertically and are then bent over in arcuate shape to terminate at points beyond the vertical centers of the arcs. The lower ends of these pipes are threaded and extend into bosses 21 cast 50 upon the baffle structure. These bosses are in communication with supply stems 22 which extend rearwardly from the vertical

baffle wall 17 and connect with regulating valves 23. The valves 23 are of the needle valve type and are in communication with the supply pipe 13. A single nozzle opening 24 is formed through the lowermost wall of each of the burner pipes and adjacent the end thereof. This opening is disposed so that its central axis, when extended downwardly, will substantially strike the upper face of the baffle floor at 15 at a point directly below the radial center of the arc of the burner nozzle pipe. It will be understood that each of the burner nozzles may 60 be separately regulated and that when desired certain of the burner nozzles may be removed to reduce the capacity of the apparatus.

In operation, liquid hydrocarbon fuel is 70 delivered to the valves 23 from the generating tank 12 by the supply pipe 13. The valves may then be opened to allow the fuel to pass through the burner nozzles and fall upon the baffle floor. This quantity of fuel 75 may then be ignited during which time the delivery of liquid fuel is continued. Eventually the burner nozzle pipes will become heated so that the fuel passing therealong will be rendered more volatile and will thus 80 be instantly ignited when passing from the burner nozzle openings 24. By this time, the fuel in combustion will cover the baffle floor entirely with flame and substantially envelop the burner nozzles, thus producing 85 an intense heat.

It will thus be seen that by the use of the burner shown a simple means is provided for producing an efficient combustion of hydrocarbon fuels and by which said combustion may be easily regulated.

While I have shown the preferred construction of my burner as now known to me, it will be understood that various changes in the combination, construction and arrangement of parts may be made by those skilled in the art without departing from the spirit of my invention as claimed.

I claim:

In a burner, a baffle floor, retaining flanges extending upwardly from three edges of the floor, a baffle wall extending upwardly from the fourth edge of the floor, bosses extending upwardly from the floor in

front of the baffle wall, supply pipes tapped into the bosses from the back side of the baffle wall, and burner nozzles tapped downwardly into the bosses in front of the baffle wall; each nozzle comprising a piece of pipe extending straight up from its boss and curved forwardly and downwardly and hav-

ing a nozzle opening discharging downwardly and backwardly so that the fuel will strike the baffle floor and rebound toward the pipes.

In testimony whereof I have signed my name to this specification.

GEORGE M. LATIMER.
